ATTORNEY

UNITED STATES PATENT OFFICE

WILLIAM H. WINSLOW, OF CHICAGO, ILLINOIS.

DESIGN FOR LATTICE-WORK.

SPECIFICATION forming part of Design No. 18,713, dated October 30, 1888.

Application filed August 31, 1888. Serial No. 224,239. Term of patent 7 years.

To all whom it may concern:

Be it known that I, WILLIAM H. WINSLOW, of Chicago, Cook county, Illinois, have invented and produced a new and original Design for Grating or Lattice-Work, of which the following is a specification, reference being had to the accompanying drawing, forming part thereof, which drawing represents a face view of my newly-invented design.

- The letters A in the drawing represent a series of open-work squares. Each square A is

connected to its adjacent squares A by curved bars d.

I claim—

The design for a lattice-work herein described, the same consisting of the series of squares A, connected by the curved bars d, substantially as shown.

WILLIAM H. WINSLOW.
